ALBION H. LOWELL, OF MANCHESTER, NEW HAMPSHIRE.

Letters Patent No. 65,922, dated June 18, 1867.

IMPROVED APPARATUS FOR FORMING MOULDS FOR PURPOSES OF CASTING METAL.

The Schedule referred to in these Letters Patent and making part of the same.

TO ALL WHOM IT MAY CONCERN:

Be it known that I, ALBION H. LOWELL, of Manchester, in the county of Hillsboro, and State of New Hampshire, have invented a new Machine for Making Moulds for Castings, of which the following is a full, clear, and exact description, reference being had to the accompanying drawings, making part of this specification, in which—

Figure 1 is a plan of my moulding machine.

Figure 2 is an elevation of the rear end of the same.

Figure 3 is a longitudinal vertical section of the same on the line $z z$ of fig. 1, the flask being in place beneath the pattern.

Figure 4 is a perspective view of one-half of the flask with the parts used in connection therewith.

Figure 5 is a vertical section through the centre of the same.

The forming of moulds in sand for castings has heretofore been done entirely by hand, which operation was slow, tedious, and laborious. My invention has for its object to accomplish this by machinery, and thus reduce the labor, and consists in a machine in which the flask containing the sand is carried automatically into a position to receive the impression of the pattern, which is forced into the sand and then withdrawn therefrom, after which the flask is carried out of the machine; and my invention also consists in certain details which will be fully described hereafter.

To enable others skilled in the art to understand and use my invention, I will proceed to describe the manner in which I have carried it out.

In the said drawings, A is the bed of the machine, and B the framework which supports the table C. D D are two pulleys of large diameter, which are secured to a shaft, a, having its bearings in the framework, and over these pulleys and two small pulleys E on a shaft, b, are stretched the endless chains c, the bearings of the pulleys E being made adjustable in the framework by means of screws d, so as to keep the chains stretched tightly as required. The flask F which contains the sand rests on a board, e, which is placed on the table C, and has projecting from its under side two pins f, which fit into the chains c, by which the flask is carried forward at the required times beneath the pattern G, which is attached by screws or otherwise to the under side of a plate or plunger, H, secured to the lower end of a bar, I, which is moved up and down in guides g in the framework, (to force the pattern into the sand and withdraw it therefrom,) by means of a connecting-rod, h, and a crank, i, on the driving-shaft J, which runs in bearings on the top of the framework. The shaft J carries a gear, j, which drives another similar gear k, on a shaft, K, which runs in bearings l, and carries at one extremity a crank, m, to which is pivoted a pitman, n, the lower end of which is pivoted to a box, o, which is pivoted on the shaft a, and carries a pawl, p, which engages with a ratchet, q, on the shaft a, and thus through the connections explained the chains c are moved intermittently at the required times to carry the flask forward beneath the pattern G, which is then pressed into the sand to form the mould. The flask which contains the sand is made as usual in two halves, the "nowel" or bottom half F, being shown in the drawings, and each half is bevelled or rounded on the outside, as seen in figs. 3, 4, and 5, for a purpose that will be explained hereafter. L is a frame which is placed over the flask F, and held in place by pins r, the inside being bevelled or inclined as seen in fig. 5. The flask is then placed beneath a "riddling machine," by which it is filled with sand to a level with the upper edge of the frame L which is then removed, leaving the sand projecting above the upper edge of the flask a distance equal to the thickness of the frame. The flask is then carried as before explained beneath the pattern G, which is forced into the sand to form the mould, at the same time pressing that portion of the sand above the upper edge 7 of the flask down into it so as to hold the sand tightly in place as required, no ramming being necessary as in the hand process. By making the outside of the flask bevelled or rounded with an edge 7 at the joint, as seen in figs. 3 and 5, no space is left for the sand to rest on when pressed down, which would be the case if made flat at the joint as heretofore, for if when the two halves of the flask were tipped over edge-wise to unite them together, any sand remained on the edge, it would be liable to fall into and injure the mould. s are guide-plates projecting from the framework, which serve to guide the flask into its proper position beneath the pattern, and prevent it from having any lateral movement. t is a bar, the upper end of which is projected up through a slot in the table C, to form a gauge or stop against which the flask strikes when it has arrived

exactly beneath the pattern. Another bar t is then brought up through the table immediately in front of the flask, the two, in connection with the guide-plates s , serving to hold it immovably in position while the pattern is being forced into the sand to form the mould, after which they are both withdrawn so as to allow the flask to be carried forward and removed from the machine.

The mechanism by which the bars are advanced and withdrawn at the required times will now be described. To the lower ends of the bars t are pivoted the levers M , which are pivoted to hangers v , projecting down from the under side of the table C , the opposite ends of the levers M being connected by links w to the levers N , which are permanently secured to rock-shafts O , having their bearings in the framework, and these shafts O are provided with cranks a' to which are pivoted the rods b' , the upper ends of which pass through holes in a guide-plate, P , secured to the framework, and are depressed by cams Q , on the shaft K , so as to raise the ends of the bars or stops t above the surface of the table C , as seen in fig. 3. As soon as the points 8 of the cams pass off the ends of the rods b' , the front ends of the levers N are depressed by means of the weights R , instantly withdrawing the bars t below the surface of the table C , as seen in fig. 2, to allow the flask to be moved forward in the direction of the arrow, and its place supplied by another. The "sprue hole" through which the metal is poured into the mould is formed by means of a tube or punch, c' , which passes through an opening in the table C , and slides into a guide-tube, S , secured to its under side, the lower end of the punch being connected with a lever, T , which is pivoted to the frame, and has attached to its opposite end a rod, e' , the upper end of which is secured by means of nuts 9 to an arm, f' , projecting from the plate H , and thus through the connections explained, as the latter is brought down the punch is forced up through the sand to form the "sprue hole" which connects with the "gates" or channels for the metal to run through. These gates are formed by the pattern G in a well-known manner. The height to which the punch c' is carried by the descent of the plate H is regulated by means of the nuts 9 on the rod e' . It is obvious that the mechanism for operating the bars or stops t , as well as that for operating the punch for making the "sprue hole," may be varied without departing from the spirit of my invention.

The machine above described is employed for making one-half of the mould, the other half being formed in a machine of similar construction, with the exception of the punch or device for making the "sprue hole," which of course requires to be in one-half of the mould only. When the article to be moulded has a flat surface on one side, the mould is made in the "nowel" or bottom half of the flask, and a flat plate only is attached to the plunger of the machine in which the other half of the flask is placed, which presses the sand down to a level with its upper edge, leaving its surface perfectly flat and smooth, as required. Instead of the flask being carried beneath the pattern and the latter forced down into the sand, a machine may be constructed in which the flask is brought over the pattern, and the latter forced up into the sand, without departing from the spirit of my invention. The arrangement first described, however, is that which I prefer. In practice the length of the endless chains c will be increased so that they may be stretched on each side of a long table forming an extension of the table C , the flasks F being successively carried by the chains first under a "riddling machine" which fills them with sand, and then, at the required time, beneath the pattern which forms the mould, after which they are carried out of the machine.

What I claim as my invention, and desire to secure by Letters Patent, is the following:

In combination with the pattern attached to the plunger, as set forth, I claim the endless chains C , the plates s , the stops or bars t , the tube or punch c' , and the flask F , as above set forth and described, and for the purpose of making moulds for castings.

ALBION H. LOWELL.
